UNITED STATES PATENT OFFICE.

HERMANN BRÜGGE, OF HANOVER, GERMANY.

DETACHABLE COVER FOR OPEN MOTOR-CARS.

1,218,050.

Specification of Letters Patent.

Patented Mar. 6, 1917.

Application filed September 23, 1915. Serial No. 52,213.

To all whom it may concern:

Be it known that I, HERMANN BRÜGGE, a citizen of Germany, residing at Ludwigstrasse 12, Hanover, in the Empire of Germany, have invented a new and useful Improved Detachable Cover for Open Motor-Cars, of which the following is a specification.

The object of the present invention is to provide an easily detachable cover or top portion, by means of which open motor cars may be quickly and conveniently converted into closed cars or carriages. The covering is constructed so as to save weight and at the same time to provide sufficient strength. The novel feature consists in having the covering constructed with a hinged rear part so as to enable this part to be thrown open if desired.

In order to render the present specification easily intelligible, reference is had to the accompanying drawing, in which similar letters of reference denote similar parts throughout the several views.

Figure 1 is a side elevation of the body of the car with the covering attached, and showing the rear section in the open position in dotted lines. Fig. 2 is a sectional plan showing one half of the cover seen from above and the other half from underneath. Figs. 3 and 4 are two part side elevations showing two different forms of constructing the movable part of the cover and Figs. 5 and 6 illustrate in side elevation and plan respectively means for securing the movable part of the covering in position.

The roof framing *a* is supported on the transverse frame *c* mounted at the back of the driver's seat and on the window frames *d* at either side of the back seat, these uprights being connected by the top framing *a* stiffened by cross ribs or bars *b*. The whole of this light framing is fastened to the upper edge of the car by means of lugs or lashes *o o* and screws, or any other suitable connection. The rear section is covered in at the back and sides by suitable flexible stuff or leather coverings or the like, attached to the rear edges of the body of the car.

In order to enable the back part or section of the covering to be thrown back or opened, the roof framing is divided trans-

versely at the rear of the back uprights *d* of the windows so that the rear part *a'* of the covering may be thrown back as indicated in dotted lines in Fig. 1, and the movable section is provided with rigid frame pieces *d'* hinged at *m* to the stationary framing *d* of the windows.

When closed the rear part *a'*, *d'*, *s* is locked to the fixed part *a* by means of known clamping devices *u*. These locking devices connect up the transverse bars *b*, *b'* (Figs. 2, 5 and 6) of the roof frame. When thrown open the rear part *s* may be supported on the back of the car or by means of chains *k* (Fig. 1) or other flexible or folding members *l*, (Fig. 3). Instead of the latter a curved telescopic member *t* may be provided on one part, which works in a sleeve *q* on the other part, the movement being assisted by means of a spring *o*. Means are provided to enable the movable rear part to be closed tightly against the fixed member. When the parts are closed one against the other the whole flexible part of the covering is, of course, properly stretched.

It is of course known to mount heavy box-like coverings on cars and it is also old to make the rear part of permanent car covering capable of being turned back. But the object of the present invention is to provide a simple framework covered with flexible material and having a rear frame also covered with stuff and capable of being thrown open.

I claim as my invention:—

In combination with a motor car having a body, a top detachably mounted on said body, the forward portion of which is rigid and the rear portion having a pivoted connection at its lower end with the forward portion and adapted to fold backward, means connecting said rear portion and the forward portion for supporting the rear portion in its lowered position and locking means for holding the parts in closed position.

In testimony whereof I affix my signature in the presence of two witnesses.

HERMANN BRÜGGE.

Witnesses:

RUDOLF GAIL,
M. M. LINDSAY.
